UNITED STATES PATENT OFFICE.

ROBERT DIXON, OF NEWARK, NEW JERSEY.

DESIGN FOR A BARBER POLE.

Application filed April 9, 1927. Serial No. 21,523. Term of patent 14 years.

To all whom it may concern:

Be it known that I, ROBERT DIXON, a citizen of the United States, residing at Newark, in the county of Essex and State of New Jersey, have invented a new, original, and ornamental Design for a Barber Pole, of which the following is a specification, reference being had to the accompanying drawing, forming part thereof.

In the drawing:—

Figure 1 is a side elevation, and

Figure 2 is a top plan view of a barber pole showing my new design.

I claim:—

The ornamental design for a barber pole, as shown.

ROBERT DIXON.
